DESIGN FOR A DOLL HEAD

Evelyn Aleshin, San Francisco, Calif.

Application April 23, 1946, Serial No. 128,900

Term of patent 7 years

(Cl. D34—4)

To all whom it may concern:

Be it known that I, Evelyn Aleshin, a citizen of the United States of America, residing at San Francisco, in the county of San Francisco and State of California, have invented a new, original, and ornamental Design for a Doll Head, of which the following is a specification, reference being made to the accompanying drawing, forming a part thereof.

Fig. 1 is a front elevation of my doll head showing my new design.

Fig. 2 is a side elevation of the doll head shown in Fig. 1, and

Fig. 3 is a rear elevational view.

I claim:

The ornamental design for a doll head, substantially as shown.

EVELYN ALESHIN.
